UNITED STATES PATENT OFFICE.

CHARLES C. BOWMAN, OF PITTSTON, PENNSYLVANIA.

GRATE FOR STOVES.

SPECIFICATION forming part of Letters Patent No. 351,896, dated November 2, 1836.

Application filed April 28, 1884. Serial No. 129,531. (No model.)

To all whom it may concern:

Be it known that I, CHARLES C. BOWMAN, of Pittston, in the county of Luzerne and State of Pennsylvania, have invented an Improvement in Grates for Stoves, of which the following is a specification.

Grates and fire-pots have both been revolved by the action of gearing, so as to agitate the fuel and shake out the ashes.

10 My improvement relates to the combination, with a revolving ring or grate, of a central dump-grate, so that the revolving portion can be used for clearing the fire by a rapid continuous rotary movement, and any clinkers 15 pass down into the central portion, and these can be dumped when the fire is to be made afresh, or even while the fire is burning, by moving the central grate. I also provide a fire-pot in the form of or having below it a 20 hanging or basket fire-pot, and rotate the same by gearing, so as to free the fuel from ashes and shake the same down, or to cause the fuel to descend from a magazine above the fire-pot. The space between the basket and the revolving 25 grate or ring allows for the removal of clinkers.

In the drawings, Figure 1 is a vertical section of the improvement. Fig. 2 is a plan, partially in section, of the fire-pot and grates; 30 and Fig. 3 shows the supporting-ring separately.

The case A of the stove is of any desired character, and it may have openings and doors, or windows, as desired. There are supports 35 b for the axis c of the circular grate d. This axis c passes through the case A, and it may be moved by a key or shaker, so as to agitate the fuel, or to dump the contents of the stove, or to remove clinkers.

40 The ring e is supported by arms e', that rest in sockets or recesses in the inclined flange e'', and upon this ring e rests the revolving grate-ring f, which is preferably in the form of a flat ring with grate-bar surface; but it may be 45 plain or corrugated, or formed with the radial bars extending from the ring 3 to the ring 2.

There are guide-fingers 4 passing from the 50 grate f down inside the ring e, and hooking beneath the bottom of such ring, so that the revolving grate can be turned around wholly or partially, and with any desired rapidity, by the action of the pinion h and the circular

rack of teeth at i on the under side of the ring 2. The fingers 4 steady the ring f, and prevent the same tipping sidewise, and the 55 ring-support e is notched, as shown in Fig. 3, to allow the hooked ends of the fingers 4 to pass down below the lower edge of this ring e as the ring f is put into its place. The axis of the pinion h passes through a tubular bearing, k, in the case A, and terminates with a square for the reception of a crank or other device, by means of which the pinion may be revolved.

Above the ring or grate f there is a fire-pot. 60 I have shown the same as formed of the ring m, with depending bars n, that are preferably slightly inclined, as shown. The lower ends of these bars n may be tied together by a ring cast with them, if desired, as shown by dotted lines at n'. These bars form an open fire-pot or the lower part of the fire-pot.

Upon the under side of the ring m there are teeth 6, and the ring and fire-pot are supported by the flanges s, that project inwardly from 75 the case A; or the ring m may be suspended below the stationary portion of the fire-pot in any desired manner.

The fire-pot can be revolved by the pinion 80 r, the teeth of which gear with the teeth 6, and the axis of the pinion passes through a tubular bearing, t, in the case A, and the outer end of such axis is square, so as to be turned by a crank. If desired, this fire-pot and grate 85 may be below the magazine v, in a self-feed- 90 ing stove.

It is now to be understood that the fuel may be shaken down and the ashes discharged by rotating or partially rotating the open fire-pot or fire-pot section, or the circular ring f; or 95 the fuel or ashes or clinkers may be dumped by the grate d, thus giving great facility for controlling the combustion of the fuel. Clinkers may also be removed or escape between the lower ends of the bars n of the fire-pot and 95 the ring f, and escape over the edge of such ring-grate and fall into the ash-pit. The grate d is adapted to dump the clinkers or the fire, and such dump-grate is preferably made to swing; but it may be made to slide or swing. 100

I claim as my invention—

1. The combination, with the hanging fire-pot, of the separate ring f, having radial bars and gear-teeth, and extending both within and

outside of the hanging fire-pot to support the fuel, and a central dump-grate below the ring *f*, to dump the clinkers that accumulate in the middle of the fire, and the pinion *h*, substantially as set forth.

2. The combination, with the ring-grate *f*, having inner and outer rings, 2 and 3, and connecting-bars, of the ring *e*, means for connecting the ring *e* and ring *f*, the casing of the stove and the arms *e'*, for supporting the rings *e* and *f*, the pinion *h*, gearing into teeth on the under side of the ring *f*, and by which the same is rotated, and the central dump-grate, *d*, below the ring *f*, substantially as specified.

3. The combination, with the stationary ring 15 *e* and its supports *e'*, of the ring *f*, having radial bars between the two rings 2 and 3, the guide-fingers 4, extending down within the ring *e*, and the pinion *h*, for revolving the ring *f*, and the central grate, *d*, below the ring *e*, 20 substantially as specified.

Signed by me this 23d day of April, A. D. 1884.

C. C. BOWMAN.
